WINDOW BRACKET

William H. Schmitt, St. Paul, Minn.

Application September 6, 1941, Serial No. 409,910

9 Claims. (Cl. 292—263)

My invention relates to an improvement in window brackets, wherein it is desired to provide a fastener suitable for use in combination with storm sashes, casement windows, basement windows, and the like.

It is the object of the present invention to provide a storm sash fastener which is removably connected at each end. Such a construction has various decided advantages over fasteners which are removable at one end only.

It is a feature of my invention to provide a means of disconnecting the bracket in such a way that the window may be quickly opened up in case of an emergency. At the same time, it is necessary that the fasteners be so constructed that they will not become accidentally disengaged. It is a feature of my invention that with my construction, the window bracket may be entirely removed in an extremely short period of time and at the same time, the construction is such that accidental disengagement is virtually impossible.

It is a feature of the preferred form of my invention that the fasteners or brackets may be entirely removed by swinging the pivoted arms forming the body of the fasteners in unison to a predetermined pivoted position, in pressing the spread arms of the bracket together under spring tension, and in pivoting the squeezed arms on an axis at substantially right angles to the normal pivotal axis of rotation of the arms in order to remove the bracket from place. By this simple means, the brackets may be entirely removed from their respective stile plates, leaving the window free to pivot open to any desired extent.

It is a further object of my invention to provide a window bracket or fastener which is equipped with two types of stile plates, one of which is designed for use in connecting one arm of the window bracket with a surface extending substantially parallel to the arm, and the other bracket of which is used to connect the other arm of the fastener to a surface extending on a plane at substantially right angles to the plane through the other bracket arm. Two of the latter brackets are used in the combination. With this arrangement, my fastener may be used to connect a casement window to a frame, to connect a storm sash to a window frame, or a basement window to its frame, the proper stile plates being selected from the assortment of three stile plates furnished with each such bracket. Thus my fastener is just as adaptable for windows pivoted on vertical axis as for windows pivoted on horizontal axis.

These and other objects and novel features of my invention will be more clearly and fully set forth in the following specification and claims.

In the drawing forming a part of my specification:

Figure 1 is a side view of a bracket connecting a storm window sash and a window frame, the view being taken on a section line through the window and frame.

5 Figure 2 is a front elevation view of the bracket in position to be opened.

Figure 3 is a section transversely through a portion of a storm sash and window frame showing the fastener in readiness for detachment.

10 Figure 4 is a view similar to Figure 3, showing the bracket partially detached.

Figure 5 is a perspective view of the attaching head of a sash fastener constructed in accordance with the principles of my invention.

15 Figure 6 is a perspective view of a type of stile plate which is designed for use in conjunction with the attaching head shown in Figure 5.

Figure 7 is a perspective view of another type of stile plate used to connect the window bracket 20 to a surface which extends substantially parallel to the pivoted arms.

Figure 8 is a perspective view of another form 25 of window bracket showing the manner of attachment and detachment thereof at both ends of the pivoted arms.

Figure 9 is a longitudinal sectional view through one of the arms shown in Figure 8 and through the stile plate used in attaching the bracket to the window frame.

30 Figure 10 is a perspective view of another type of window fastener and two forms of stile plates which may be used in conjunction therewith.

Figure 11 is an elevation view of the end of one 35 of the arms of the bracket shown in Figure 10 and its relationship with its respective stile plate.

Figure 12 is an elevation view of the other arm of the bracket shown in Figure 10 and its relation with its respective stile plate just before attachment thereof.

40 The storm window bracket or fastener A includes an arm 10 and a second arm 11 pivoted together and connected by means of a pivot bolt 12 or the like. The arms 10 and 11 are preferably provided with enlarged ends 13 and 14 respectively through which the pivot bolt 12 extends and washers 15 of friction creating material are inserted between the heads 13 and 14 and between the heads of the bolt 12 and the adjacent enlarged end 14 in order to resist pivotal movement between the arms 10 and 11.

45 These friction washers 15 hold the pivot arms 10 and 11 in any set adjusted position, and the friction may be regulated by adjustment of the nut on the bolt 12. The end of the arm 11 extends beyond the enlarged head 14 and is bent at right angles to form a flange or lug 16 which limits the pivotal movement of the arms so that the arms 10 and 11 cannot move into alignment. 50 This fact is true because the flange 16 on the arm 11 strikes the body of the arm 10 adjacent

55 to the pivot bolt 12. The flange 16 is so located that it will not interfere with the pivoted movement of the arms 10 and 11.

60 The flange 16 is so located that it will not interfere with the pivoted movement of the arms 10 and 11.

the head 13 as shown in Figure 1 of the drawing to limit pivotal movement in this direction.

An ear 17 is provided on the arm 11 which extends over the arm 10 and is provided with a downwardly extending flange 19 to limit the spreading of the arms 10 and 11 apart. The arms 10 and 11 are offset at 20 and 21 respectively so as to spread the free ends of the arms 10 and 11, and these arms are urged apart under spring tension.

The ear 17 acts as a locking lug in one pivotal position of the arms 10 and 11 as will be later described.

The free ends 22 and 23 of the arms 10 and 11 are enlarged as best noted in Figure 5 of the drawing, and are provided with a locking device 24 by means of which the arms are disengagably secured to their respective stile plates 25 and 26. The locking lugs 24 are formed as best illustrated in Figure 5 of the drawing, being provided with a cylindrical bearing portion 27 and a flat T-shaped head 28. Each of the locking devices 24 is designed to fit through a suitable recess 30 in the respective stile plates 25 and 26. Each recess 30 includes a circular opening having opposed slots 31 extending radially therefrom as illustrated in Figures 6 and 7 of the drawing. The T-shaped head 28 may extend through any of the recesses 30 when the T-shaped head 28 is in proper pivoted relation with the opening, and once the head 28 has projected through the opening, the head provides shoulders 32 to engage on the opposite side of the stile plate to lock the bracket arms in place.

In the preferred form of construction, the opposed slots 31 extend longitudinally of the stile plates 25 and 26 while the locking means 24 is formed with the T-shaped head extending transversely with respect to the arms 10 and 11. Thus in every position of the bracket arms 10 and 11, except the position shown in Figures 3 and 4 of the drawing, the T-shaped head 28 will not coincide with the openings 30. For example, in the open position shown in Figure 1 of the drawing, the locking heads 24 will not align with the openings in the stile plates 25 and 26, and in this position the fastener or bracket A may not be removed. This is also true of the position shown in Figure 2 of the drawing, as in this construction the heads 28 of the locking means 24 extend at right angles to the slots or notches 31. When the bracket arms have been pivoted into the position shown in Figures 3 and 4 of the drawing, however, in which position the arms extend outwardly at substantially right angles from the window, the heads 28 align with the notches 31 and the brackets may be removed.

Due to the normal outward spring tension of the arms 10 and 11, the brackets will not become accidentally disengaged even when in the position shown in Figures 3 and 4. If it is desired to remove the brackets, however, when the arms are in this position, the arms are squeezed together as indicated by the position shown in dotted outline in Figure 3, at which time the locking means 24 of the arm 11 is removed from the recess 30 in the stile plate 26. By opening the window sash 25 while the bracket arms are held in this position, the arms may be swung out of contact with the stile plate 26 to permit removal of the locking means 24 on the arm 10 from the stile plate 25. A simpler manner of removing the fasteners or brackets, however, is to pivot the arms 10 and 11 in the manner shown in Figure 4 of the drawing, thus removing the

locking means 24 from the stile plate 25. Thus by merely pulling the two brackets or fasteners into a substantially horizontal position, squeezing the arms of each fastener together, and pivoting the same inwardly, both fasteners may be removed in an extremely short period of time.

As is common in brackets of this general type, the ears 17 provide a means of locking the storm sash 33 to the window frame 34. From an observation of Figure 1 of the drawing, it will be clear that when the storm window has been closed, the arms 10 and 11 will assume parallel relationship in the manner illustrated in Figure 2. As the arms 10 and 11 are of the same length, these arms may then be pivoted through 180° until the body of the arms 10 and 11 is above the stile plates 25 and 26. In this position the ear 17 prevents outward movement of the arm 10 with respect to the arm 11, thus locking the storm sash in closed position.

It will be noted that the stile plate 26 has its opening 30 in a central offset portion 34' so that the locking head 24 may extend between this central offset portion and the body of the window frame 34.

In the construction shown in Figures 8 and 9 of the drawing, a window fastener or bracket B is designed to be disconnected at either end from corresponding stile plates. In the fastener B I provide a pair of arms 35 and 36 having enlarged connecting ends connected by means of a pivot bolt 37. Friction washers 39 are positioned between the arms, and the arm 36 is provided with an extension 40 terminating in a second enlarged head 41 which is parallel to and spaced from the head of the arm 36. The extension or connecting portion 40 acts in the same manner as the lug or flange 16 of the fastener A to prevent the arms 35 and 36 from moving into alignment. Thus in any position of the storm window or the like to which the bracket is attached, the window may be closed without first moving the arms 35 and 36 out of alignment.

A spring plate 42 is connected to each of the arms 35 and 36 by means of a pair of ears 43 which encircle the arm at one end of the plate. The plates 42 are provided with additional oppositely disposed ears 44 at the other end thereof which loosely encircle the arms 35 and 36. A pair of opposed notches 45 on each arm 35 and 36 provide shoulders to engage the ears on the plate 42 when this plate is in one extreme position, as illustrated in Figures 8 and 9 on the arm 36. When moved to the other extreme position as illustrated in Figure 8 on the arm 35, the ears on the plate 42 ride over the ends of the notches 45, the ears 43 springing sufficiently so that this action may take place. Each of the spring plates 42 is provided with a notch 46 to engage about a pivot pin in a manner which will be now described.

The stile plates to which the arms 35 and 36 are attached may be of the type generally indicated by the numeral 47 or may be of a type indicated by the numeral 49. The stile plate 47 is right angular in shape, having an attaching flange 50 drilled to accommodate screws or fastening means, and a flange 51 from which a pivot pin 52 projects. An encircling groove 53 is provided on the pin 52 to accommodate the bifurcated end of the associated plate 42, the notch 46 being of a width to accommodate the small diameter portion of the pin 52 at the base of the groove 53, but being too narrow to fit about the entire body of the pin 53. Thus when the

arm 35 is attached to the stile plate 47, the pin 52 extends through the circular opening 54 in the free end of the arm 35, and the spring plate 42 is moved upwardly so that the bifurcated end thereof engages in the groove 53 to prevent disengagement of the arm 35 and the pin.

The stile plate 49 is provided with aligned attaching ends 55 through which holes are drilled to accommodate screws or other fastening means and an offset central portion 56 accommodating a pivot pin 57. As shown in Figure 9 of the drawing, the pivot pin 57 is provided with an annular groove 59 in which the bifurcated end of the spring plate 42 associated therewith may engage. Thus when in the position shown in full outline in Figure 9, the spring plate holds the bracket arm 36 to the stile plate against accidental disengagement therefrom, but permits free pivoting of the bracket arm with respect to the stile plate.

The fastener C illustrated in Figures 10, 11, and 12 of the drawing also may be disconnected from its associated stile plates 60 and 61 when it is so desired. The fastener or bracket C comprises a pair of arms 62 and 63 having enlarged ends which are connected by an adjusting bolt 64. Friction washers 65 are interposed between the arms 62 and 63 so as to create friction tending to hold the arms in any set adjusted relation. A lug 66 on one of the arms 62 prevents the arms 62 and 63 from moving into alignment to facilitate the closing of the window from wide open position. Each of the arms 62 and 63 are provided with enlarged circular heads 67 and 69, respectively, having circular openings 70 and 71 therein to accommodate the pivot pin on the stile plates 60 and 61.

The stile plate 60 is provided with an attaching flange 72 drilled to accommodate screws or other fastening means. A flange 73 extends at substantially right angles to the flange 60 and is provided with pivot pin 74 extending at substantially right angles thereto. A flange 75 extends upwardly from the plate 60 substantially parallel to the flange 73 and is provided with a tip end 76 which extends toward the pin 74 and terminates in spaced relation thereto. The rounded flat end 67 of the arm 62 is provided with a notch 77 through which the tip end 76 of the flange 75 may pass. As shown in Figure 11 of the drawing, the flange 75 is spaced from the flange 73 sufficiently to permit the arm 62 to be positioned between these flanges. In any angular position of the arm 62 other than the position in which the tip end 76 may fit through the notch 77, the tip end 76 will engage over the face of the rounded end of the arm 62 and prevent its disengagement therefrom. In one angular position of the arm 62 with respect to the stile plate 60, however, the arm 62 may be engaged or disengaged from the pin 74.

A stile plate 61 includes a pair of aligned attaching ends 79 which are drilled to accommodate screws or other attaching means. A pin 81 projects outwardly from the central portion of the plate 61 to fit into the circular opening 71 of the arm 63. An ear 82 projects forwardly from the central portion of the stile plate 61 and includes a flange 83 which is bent substantially parallel to the plate 61 and in spaced relation thereto. As seen in Figure 12 of the drawing, the flange 83 is spaced from the central portion of plate 61 sufficiently to permit the arm 63 to extend between this flange and the plate 61.

A notch 84 is provided in a rounded head 69 to accommodate the flange 83. When the arm 63 is in one specific angular relation with respect to

the stile plate 61, the arm 63 may slip onto or off from the pin 81. In any other angular position of the rod 63, the flange 83 overlies the face of the head 69 of the arm 63, and holds the arm 63 engaged thereto.

The notches 77 and 84 may be so positioned that one of the arms may be detached while the bracket is in one angular position and the other of the arms may be detached in another angular position. If desired, these angular positions may coincide so that both ends of the bracket may be detached at the same time. It is preferred, however, in this construction to have one of the brackets detachable in one angular position and then by pivoting the bracket slightly, the other end or other arm may be removed.

In packaging the present device, I prefer to include a pair of brackets such as A, B, or C and to include with these brackets one pair of stile plates such as is shown in Figures 7, 9 or 12, and to furnish two sets of stile plates of the type shown in Figure 6 or 11 and shown at the left-hand side of Figure 8. In other words, for each bracket A I provide one stile plate 26 and two stile plates 25. For the bracket B I provide one stile plate such as 49 and two stile plates such as 47. With the bracket C I provide one stile plate 61 and two stile plates 60. The stile plates are designed to fit on either end of the bracket and by providing extra stile plates of the type described, both ends of the bracket may be provided with right angular brackets to engage surfaces at right angles to the plane of operation of the bracket arms. My bracket is thus made suitable for use for an extremely great combination of cases, and may fit any one of a great number of installations.

It will be seen that with the type of construction shown in Figures 1 through 7 of the drawing, it is only necessary to pivot the bracket arms in unison to a horizontal position and to pivot the pivotally connected ends of the brackets inwardly of the window in order to remove the brackets. Thus in a simple movement, the brackets may be detached in an emergency or when it is desired. The brackets are not supported either by the window sash or by the window frame during the period they are not in use, and therefore the windows may be handled without danger of having the brackets project through the glass panes of an additional sash to break the same.

While I have discussed the bracket as being particularly designed for use in conjunction with pivoted windows of one type or another, it is obvious that the brackets may be similarly used on doors or closures of various types. Thus when I mention pivoted windows in the claims, I desire to have it understood that doors or other pivoted closures could be similarly connected. Furthermore, while I have discussed pivot pin connections in which one part of a bracket is secured to a stile plate by means of a pivot pin connection which fits into a suitable recess in the other element, it is obvious that pivot pins could be on either of the elements and the cooperating recess in the other of these elements.

In accordance with the patent statutes, I have described the principles of construction and operation of my window bracket; and while I have endeavored to set forth the best embodiments thereof, I desire to have it understood that these are only illustrative of a means of carrying out my invention and that obvious changes may be made within the scope of the following claims

without departing from the spirit of my invention.

I claim:

1. A storm sash fastener for connecting a storm sash and a frame, said connector including a pair of pivotally connected arms, a stile bracket connected to the window frame, a second stile bracket secured to said storm sash, an offset means in said arms to space the free ends of said arms apart under spring tension, pivotal connecting means connecting the free ends of said arms to said stile brackets, said pivotal connecting means being movable into alignment in closed position of said storm sash, and cooperable means on the free ends of said arms and on said stile brackets operable in one angular position of said aligned window brackets when said arms are flexed together at the free ends thereof for detachably connecting said arms to said brackets.

2. A window bracket for use in connecting a pivoted window and a frame comprising a pair of jointed arms, a stile plate on the window, a stile plate on the frame, said arms being relatively pivotal from a side by side parallel relationship to a substantially end to end relation, and means detachably connecting said pivotally connected arms to both of said stile plates, said means holding said arms from simultaneous detachment unless said arms are in said side by side parallel relationship and in a predetermined angular position.

3. A window bracket for use in connecting a pivoted window and a frame comprising a pair of jointed arms, said arms being relatively pivoted from a side by side parallel relationship to a substantially end to end relationship, means pivotally and detachably connecting one of said arms to the window, and means pivotally and detachably connecting the other of said arms to the frame, and connecting means holding said arms from simultaneous detachment unless said arms are in side by side parallel relationship and in a predetermined angular position.

4. A window bracket for use in connecting a pivoted window and a frame comprising a pair of jointed resilient arms, said arms being relatively pivotal from a side by side parallel relationship to a substantially end to end relation, said arms being close together adjacent the joint and normally spaced apart throughout the rest of their length, the resilience of said arms permitting the same to be sprung together at their free ends, means pivotally and detachably connecting one of said arms to the window, and means pivotally and detachably connecting the other of said arms to the frame, said connecting means holding said arms from simultaneous detachment unless said arms are in said side by side relation and in a predetermined angular position, the flexing together of the free ends of said arms then simultaneously detaching said arms.

5. A window bracket for use in connecting a pivoted window, and a frame comprising a pair of jointed resilient arms, said arms being relatively pivotal from a side by side parallel relationship to a substantially end to end relation, said arms being close together adjacent the joint and normally spaced apart throughout the rest of their length, the resilience of said arms permitting the same to be sprung together at their free ends, a stile plate on said window, a second stile plate on said frame, means on each of said arms pivotally and detachably connecting each

arm to a respective stile plate, said connecting means holding said arms from simultaneous detachment unless said heads are in side by side relation and in a predetermined angular position, the flexing together of the free ends of said arms then simultaneously detaching said arms.

6. A window bracket for use in connecting a pivoted window and a frame comprising a pair of jointed resilient arms relatively pivotal from a side by side position to a substantially end to end position, the free ends of said arms being supported in spaced relation, means detachably connecting one of said arms to said window, and means connecting the other of said arms to the frame, means on the window and frame respectively holding said connecting means from disengagement unless said arms are in side by side relation and in one angular position, said connecting means and holding means then being disengageable by flexing the arms together.

7. A window bracket for use in connecting a pivoted window and a frame comprising a pair of jointed resilient arms relatively pivotal from a side by side position to a substantially end to end position, the free ends of said arms being supported in spaced relation, a stile plate on said window, a second stile plate on said frame, means detachably connecting one of said arms to one of said stile plates, and means detachably connecting the other of said arms to the other of said stile plates, means cooperable between said stile plates and said connecting means holding said connecting means from disengagement unless said arms are in side by side relation and in one angular position, said connecting means then being disengageable by flexing the arms together.

8. A window bracket for use in connecting a pivoted window and a frame comprising a pair of jointed resilient arms relatively pivotal from a side by side position to a substantially end to end position, the free ends of said arms being normally supported in spaced relation, means pivotally and detachably securing the free end of one arm to said window, means pivotally and detachably securing the free end of the other arm to said frame, cooperable holding means on said window and on said frame holding the securing means from disengagement unless said arms are in side by side relation and in one angular position, the flexing of one arm toward the other then disengaging said one arm from its holding means, the other securing means being pivotal out of engagement with its respective holding means.

9. A window bracket for use in connecting a pivoted window to a frame comprising a pair of jointed arms having free ends normally supported in spaced relation, means detachably and pivotally securing the free end of one arm to the window and means detachably and pivotally securing the free end of the other arm to said window, said arms pivoting into side by side relation when said window is in closed position and swinging in unison about their respective securing means, holding means cooperable with said securing means to hold said securing means from simultaneous detachment unless said arms are in side by side relation and pivoted to a predetermined angular position, said arms being swingable about an axis at substantially right angles to the axis of said securing means to detach said arms.

WILLIAM H. SCHMITT.
